UNITED STATES PATENT OFFICE.

JOHN N. NELSON, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND.

DESIGN FOR A TEMPLE FOR OPHTHALMIC MOUNTING.

Application filed November 17, 1927. Serial No. 24,194. Term of patent 14 years.

To all whom it may concern:

Be it known that I, JOHN N. NELSON, a citizen of the United States of America, residing at Providence, county of Providence, State of Rhode Island, have invented a new, original, and ornamental Design for a Temple for Ophthalmic Mounting, of which the following is a specification, reference being had to the accompanying drawing, forming a part thereof.

The figure is a perspective view of a temple for ophthalmic mounting, illustrating my new design.

I claim:

The ornamental design for a temple for ophthalmic mounting, substantially as shown.

JOHN N. NELSON.
